UNITED STATES PATENT OFFICE

ROBERT H. MOORE, OF NEW YORK, N. Y.

BOOKMARK

Application filed April 12, 1929. Serial No. 354,523.

This invention relates to book marks, and particularly the type which is interchangeable, as distinguished from book marks which are permanently attached to or form part of the book itself.

The principal object of the invention is to provide an efficient and improved interchangeable book mark, which will in no way interfere with the using, storage, or shelving 10 of the book, will in no way injure or mar the book or the furniture upon which the book may be placed, will properly adapt itself to the efficient marking of any part of the book, which will have means for identification of the book mark or of the book with which it is used, and which will have means for cutting the pages of the book, particularly the pages of finely bound editions wherein some or all of the leaves are 20 frequently left in uncut state.

Other objects and advantages will hereinafter appear.

In the accompanying drawings,—

Fig. 1 shows a front elevation of the book mark, with the cutter or cutting element thereof shown in operative state.

Fig. 2 is a side elevation of the book mark shown in Fig. 1.

Fig. 3 shows in perspective a rear view 30 of a book, and of the book mark shown in Fig. 1, as the latter appears when in operative condition in connection with the book.

Fig. 4 shows a cross-sectional elevation of 35 the book and book mark shown in Fig. 3.

Figs. 5 and 6 show, respectively, a plan view and cross-sectional elevation of a detail of the invention.

Figs. 7, 8, 9 are respectively a perspective 40 view, front elevation, and side elevation showing a modification of the invention.

Fig. 10 shows another modification of the invention.

The book mark comprises a ribbon or double-cord 1 which is tied to a holder 2 in the

manner shown. Said holder consists of a single piece of wire 3 of metal or any other suitable material, which is bent or configurated to form a flattened eye 4 to which the cord 1 is directly tied, and from said eye diverge a pair of legs 5 in the manner shown. The ends 6 of the legs 5 are curved toward each other, as illustrated. Between the eye 4 and the legs 5 is formed a double stem portion 7, part of which together with said eye are bent obliquely to the plane in which the legs 5 lie, as indicated in Fig. 2, and the stem is provided with registering curved portions 8 which form a ring 9. Against the ring portion 9 is located the head 10 of a paper cutter 11, and a rivet 12 passes through said ring and a hole 13 formed in the cutter-head 10, whereby the wire 3 and the cutter are secured to each other. In assembling the parts the rivet 12, which initially is formed as 65 shown in Figs. 5, 6, is flared out to form the head 14 which bears against the underside of the cutter 11, the upper or round-head 15 of the rivet, which head is springy, overlaps the ring 9 and bears under tension against the 70 opposite side of the cutter, while cut-out portions 16 in the rivet permit the stem portions 7 projecting from opposite sides of the ring 9 to pass out from the head 15 and prevent rotation of the rivet relatively to the 75 stem 7, in which manner the cutter 11 is enabled to swivel under tension about the rivet 12 as a pivot, from an operative or cutting position shown in Fig. 1 to an inoperative or folded position shown in Figs. 3, 4. The 80 cutter 11 may be made of any suitable metal or any other substance suitable for the purpose.

When utilizing this book mark the holder 2 thereof is inserted between the back-binding 17 and the leaves 18 of the book 19, in the manner illustrated in Figs. 3, 4, and the cords 1 may be then utilized for book marking purposes in the usual manner. While the wire 3 and cutter 11 are here shown as 85 90

of substantial thickness for convenience of illustration, the same may in actual practice be made of very thin, springy, and flexible material, whereby when the book is utilized or in closed state the holder 2 will in no way interfere with the binding, and will in no way injure or mar any portion of the book or the furniture upon which it may be placed. The inclination of the eye 4 maintains it below the edge 20 of the book cover 21, as shown in Fig. 4, thereby preventing any contact of the eye portion with anything outside of the limits of the book covers. As the legs 5 tend to spring outwardly the holder 2 is thereby firmly maintained in its place within the binding, and the curvature of its terminals 6 prevents any undue abrasion thereof against the binding. The configuration of the legs 5 and their terminals 6 are also conducive to permitting the holder 2 to tilt to any position, as shown in Fig. 3, whereby the eye 4 is permitted to assume any position along the leaves of the book to conform with any position of the cord 1 within the leaves. The oblique form of the eye 4 also serves to limit the inward placement and downward position of the holder 2 within the binding. The cutter 11 may be made of such material that it will also serve the purpose of an identification card which will be found convenient for writing or printing thereon the name of the owner of the book-mark or of the book, or the name of the seller of the book, or any other desired information. Normally this device is utilized for the above described usual book-marking functions, in the position and manner illustrated in Figs. 3, 4, but in case the book user finds that some of the leaves of the book are uncut, as occurs frequently and often unexpectedly, he withdraws the book mark and holder 2 from the book 19, and turning the cutter 11 about its pivot 12 disposes it to the position shown in Fig. 1 or its operative condition. He may then grasp the holder 2 in the manner of a handle and proceed to cut up the pages or leaves with the cutter 11 conveniently and efficiently, after which he may fold back the cutter to a position between the legs 5 of the holder 2 and reinsert the entire device between the back-binding and leaves of the book, as indicated in Figs. 3, 4.

According to the modification shown in Figs. 7, 8, 9, the stem 7 projecting directly from the legs 5 of holder 2 is formed into a closed ring 9a which constitutes the terminal of the holder, and a rivet 12a which secures the holder 2 to the cutter 11, similarly to the rivet 12, is provided with a portion 22 which projects beyond the terminal ring 9a and the cutter 11, as shown. The portion 22 is bent obliquely at 23 in the manner of the eye 4, and being provided with a slotted opening 24, Fig. 7, serves the same purpose as the eye 4 for tying a marker cord 1 thereto. In

the modification shown in Fig. 10, the head 10 of cutter 11 extends beyond the limit shown in Figs. 1, 8, and it is provided with an obliquely bent portion 4a having a slotted opening 4b, which portion and opening serve the same purpose as the eye 4 for tying the marker cord thereto. 70

Variations may be resorted to within the scope of the invention, and portions of the improvements may be used without others. 75

Having thus described my invention, I claim:—

1. A book mark device having the combination of a marker cord, means for attaching said cord to said device, means for retaining the device between the back binding and leaves of a book, and a leaf cutting element, said element being pivoted relatively to said retaining means whereby it may be disposed side by side with said retaining means or opposite thereto. 80

2. A book mark device having the combination of a marker cord, means for attaching said cord to said device, spring means for retaining the device between the book binding and leaves of a book, and a leaf cutting element, said element being pivoted relatively to said retaining means whereby it may be disposed side by side with said retaining means or opposite thereto. 90

3. A book mark device having the combination of a marker cord, means for attaching said cord to said device, spring means comprising a pair of legs adapted to bear away from each other for retaining the device between the back binding and leaves of a book, and a leaf cutting element, said element being pivoted relatively to said retaining means whereby it may be disposed side by side with said retaining means or opposite thereto. 100

4. A book mark device having the combination of a marker cord, means for attaching said cord to said device, means for retaining the device adapted to be inserted between the back binding and leaves of a book, and a leaf cutting element, said element being pivoted relatively to said retaining means whereby it may be disposed side by side with said retaining means or opposite thereto, said element embodying means to limit the insertion movement of said retaining means. 110

5. A book mark device having the combination of a marker cord, means for attaching said cord to said device, means for retaining the device adapted to be inserted between the back binding and leaves of a book, a leaf cutting element, said element being pivoted relatively to said retaining means whereby it may be disposed side by side with said retaining means or opposite thereto, and means to limit the insertion movement of said element. 120

6. A book mark device having the combination of a marker cord, means for attach-

ing said cord to said device, means for retaining the device between the back binding and leaves of a book, and a leaf cutting element, said element being pivoted relatively to
5 said retaining means under tension whereby it may be disposed side by side with said retaining means or opposite thereto.

Signed at the city of New York, in the county of New York, and State of New York, this
10 11th day of April, A. D. 1929.

ROBERT H. MOORE.
